CALCULATING MACHINE AND CASH DRAWER

Ernest Racz, Detroit, Mich., assignor to Burroughs Adding Machine Company, Detroit, Mich., a corporation of Michigan

Application December 20, 1930, Serial No. 503,690
Renewed November 22, 1934

21 Claims. (Cl. 235—22)

This invention relates to a combination calculating machine and cash drawer of the type in which a small calculating machine is combined with a cash drawer to form a unit that is useful for a wide variety of purposes.

The object of the invention is to provide a greatly improved combination of the character mentioned, especially one having improved cash drawer controls for adapting the unit to a wide variety of uses.

The more particular objects of the invention will appear in the following specification and drawings.

An embodiment of the invention is shown in the accompanying drawings, in which:

Fig. 1 is a right side elevation of the machine with a portion of the casing removed to show some of the internal mechanism;

Fig. 2 is a right side elevation of the rear portion of the machine shown in Fig. 1, the parts being shown in normal condition;

Fig. 3 is a perspective view of the latch for the cash drawer together with certain controls therefor;

Fig. 4 is a detail, side elevation of the locking device for the cash drawer showing the parts in normal condition;

Figs. 5 and 6 are views similar to Fig. 4 with the parts shown in different positions;

Fig. 7 is a sectional detail on the line 7—7 of Fig. 4;

Fig. 8 is a perspective view of a modified form of an operating part which may be substituted in the machine to convert the machine to one that will open the cash drawer upon every machine operation;

Fig. 9 is a perspective view of another modified part which may be used to convert the machine to one that will open the cash drawer upon every machine operation except a "non-add" operation.

The calculating machine

The calculating machine illustrated is of a type on the market known as the Burroughs Portable. An understanding of its details is not necessary for an understanding of the present invention and the description of the machine will consequently be confined to a general outline.

Referring to Fig. 1, the machine is provided with a plurality of depressible amount keys 18 on which items may be entered. When the machine is operated, these amount keys control the differential positions to which actuator racks 11 (Fig. 2) move that control type bars 12 adapted

to print on a piece of paper 13 on the platen 14 of the paper carriage 15 of the machine.

The machine is actuated by a main drive shaft 16 which may be either hand or motor driven, preferably the latter. The machine is operated by first giving it a "forward stroke" which rocks the shaft 16 counterclockwise from its Fig. 1 position after which it is given a "return stroke" in the opposite direction which returns it to its original position. Connected to the main drive shaft 16 is a plate 17 to which is connected a rearwardly extending link 18 that, in turn, is connected to the arm 19 of a pivoted member 20 that operates certain portions of the machine and is connected to the dash pot (not shown). It is to be observed that, at every operation of the machine, the link 18 moves rearward and is then returned forward.

The machine is provided with a register or registers (Figure 2) for receiving items and from which totals and subtotals may be taken. The controlling arm for a register is shown as 21 at the rear of Fig. 1. This arm is moved and controlled by a main pitman 22 whose front end is forked or U-shaped. The lower fork has a hooked end 23 and the upper fork has a pawl 24 pivoted to it. The movements of the main pitman 22 are controlled by studs 25 and 26 on the plate 17 connected to the main driving shaft 16.

When the machine is conditioned for addition, the parts are in the position shown in Fig. 1. During the forward stroke neither of the studs 25 or 26 causes any operation of the main driving pitman, but the stud 26 moves past the pawl 24 and behind its shoulder. At the beginning of the return stroke, the stud 26 engages the shoulder on pawl 24 and moves the pitman 22 rearwardly which engages the register with the actuator racks. Near the end of the return stroke of the machine, the stud 25 engages the hooked end 23 of the lower branch of the pitman and returns the pitman forwardly to withdraw the register from the actuator racks.

The machine is provided with certain control keys such, for example, as a total key T, a subtotal key ST, a repeat key R and an error key E. The machine of the present application also has a "single item" key SI which will be later described.

When the total key T (Fig. 1) is depressed, a lever 30 pivoted at 31 is rocked counterclockwise. This thrusts a link 32 downward which swings a pawl 33 pivoted on the lower branch of the main pitman 22 into the path of the stud 25. Downward movement of the lever 30 also moves downward a member 34 pivoted on the main pitman 22.

22. The outer end of this member is hook shaped and, near the center, it has a projection for disengaging the pawl 24. Depression of the total key thus renders the pawl 33 active and disables the pawl 24.

At the beginning of the forward stroke with the total key depressed, the stud 25 engages the end of pawl 33 and moves the main pitman 22 rearwardly which engages the register with the 10 actuator racks. Near the end of the forward stroke the stud 26 engages the hooked end of member 34 and pulls the pitman 22 forward again thus moving the register out of engagement with the actuator racks. During the return stroke 15 neither of the studs 25 or 26 acts on the pitman as pawl 24 is disabled and the stud 25 does not engage hooked end 23 of pitman 22 because the pitman is already forward.

When a subtotal is taken, depression of the subtotal key ST rocks a lever 35 downwardly which moves the link 32 downward to render the pawl 33 active, but depression of the subtotal key does not move the member 34 downward and hence the pawl 24 is not disabled. The result is that, at the 25 beginning of the forward stroke of the machine in subtotaling, the register is rocked into engagement with the actuator rack but it is not pulled out of engagement at the end of the forward stroke as it is in total taking. In fact, it is not 30 pulled out of engagement until near the end of the return stroke when the stud 25 engages the hooked end 23 of the lower branch of the pitman.

Cash drawer

35. The cash drawer is mounted in a housing 40 having a top 41 provided with a relatively large substantially rectangular opening. Cross braces 42, of which one is shown in Figs. 1 and 2 extend across this opening, one at the front and one at the rear, and, resting on these cross braces, is the base pan 43 of the calculating machine, the machine being attached to the pan. The top 41 of the housing 40 is bent upward around the edges of the opening in it to form an upstanding flange 44 which extends upward around the sides and ends of the opening. The base pan 43 of the machine has an upwardly extending flange 45 on its sides and ends, and when the pan is in position the flange 45 engages against the inner side of the flange 44. It will be noted that flange 44 is slightly shorter than flange 45. Mounted on the top edge of the flange 45 is a sound deadening strip 46 and fitting over this strip is the shouldered lower portion 47 of the casing 48 of the calculating machine. The shoulder of the casing rests on the strip 46 and extends downward on the outside of flange 44. The base pan of the calculating machine thus forms the top of the cash drawer housing as well as a pan and support for the machine. The calculating machine casing merges with the housing 40-41 in a neat manner with the casing outside of flange 44 to enable the structure to shed water and dirt. The sound deadening strip 47 serves to deaden the 55 noise of the calculating machine that might otherwise be caused by its being mounted on top of the hollow housing containing the cash drawer.

The cash drawer 50 is preferably constructed of metal and it is mounted in the housing 40 so as to be movable from the closed position of Fig. 1 to an open position and vice versa. For this purpose it is mounted upon rollers 51 of which one is shown at the left end of Fig. 1. The drawer is urged outward by a spring 52 (Fig. 1) but is normally restrained from moving by a latch 53.

The latch 53 is fixed to a shaft 54 (Fig. 3) journaled in brackets on the rear cross brace 42. The shaft 54 is urged in a clockwise direction as shown in Fig. 3 by a spring 55 connected at one end to a stationary stud and at its other end to the arm 57 of a yoke 56 fixed to the shaft 54.

When the drawer is closed, the latch 53 normally occupies the position shown in Figs. 2 and 3 where the shoulder of the latch is positioned in a notch 58 in a member 59 on the cash drawer. The latch thus restrains the cash drawer against forward movement but the drawer may be released by rocking the latch counterclockwise a short distance.

Automatic control of cash drawer in total taking

Combination machines of the character described are used in small businesses where a plurality of items are to be entered on the machine, printed and registered, a total taken and 20 printed, and the customer handed a slip showing the amount of each item and the total. Also, when the total is taken, the cash drawer should be opened so that the proprietor or clerk can 25 put the cash in the drawer and make change.

When operations are being started, it is sometimes desirable to make sure that the machine is clear. This is done by depressing the total key and taking a total. If the machine is clear, a special character will be printed without any 30 figures or digits. If it is not clear, the amount in the register will be printed. It is not desirable to have the cash drawer open during this 35 totaling operation if the register is clear. Provision has accordingly been made to automatically open the cash drawer when the machine is operated to take a total, with which is combined the feature that, if the register is clear, the total taking operation will not release the drawer. Viewed from another angle the latter feature is 40 one in which the opening of the cash drawer is a signal to the operator that the register was not clear when he started operations. There are other controls for the cash drawer which are combined with the above as will be later described.

Referring to Fig. 2, a releasing pin 60 is mounted in the pan 43, the pin being urged upward by a spring 61. The pin is positioned so that its lower end is normally over an irregular shaped member 62 (Fig. 3) pivoted at 64 to a broad plate-like extension of the yoke 56. The member 62 is urged counterclockwise, as viewed in Fig. 3, by a spring 66, the member being limited in its movement by the engagement of a projection 67 on it with a lateral lug 68 on a locking link 69 that will be later described. The outer end of member 62 rests on top of the plate-like extension 65 of yoke 56 so that when the releasing pin 60 engages the member 62 and moves it downward the extension 65 will be rocked 55 downward and the yoke 56 rocked to release the latch 53.

The releasing pin 60 is automatically depressed at the appropriate time by the clockwise rocking action of a yoke 70 (which will be called the releasing yoke) pivoted at 71 and provide with an arm 72 positioned over the upper end of the pin 60. The yoke has another irregular shaped arm 73 carrying a pivoted pawl 74 on its upper end, the pawl being urged counterclockwise by a spring 75 but being normally limited by engagement with a stud 76 (Fig. 2) on one arm 77 of a yoke 78 pivoted at 79, the other arm 80 of 75

the yoke being limited against a stationary stud 84 on one of the side plates of the machine.

The releasing yoke 70 which depresses the releasing pin 60 is controlled and actuated as follows:

Referring to Fig. 1, a lever 82 is pivoted near its center to one of the side plates of the machine and urged clockwise by a spring 83. The forward end of this lever is positioned under a lug 84 on the link 32 which, as will be recalled, is moved downwardly upon depression of either the total or the subtotal key. The rear end of the lever 82 carries a stud 85 (Fig. 2) positioned in an inclined slot 86 in the upper end of one arm 15 87 of a pivoted yoke 88. The other arm 89 of this yoke carries a stud 90 positioned to engage one arm 91 of a pivoted yoke 92. The other arm 93 20 of the yoke 92 carries a stud 94 positioned under the end of a long pawl 95 pivoted at 96 and urged clockwise by spring 97. The pivot 96 of the pawl 95 is carried by a downwardly extending portion 98 of one of the side arms of a bail 99 having another side arm 100, both of the side arms being pivoted loosely on a shaft 101 which carries the 25 printing hammers 102 of the printing mechanism of the calculating machine. The bail 99 extends across behind all the printing hammers and is urged clockwise by a spring 103.

When either the total or the subtotal key is depressed, the link 32 is thrust downwardly which rocks the lever 82 counterclockwise. The stud 85 moves upward in the inclined slot 86 and rocks the yoke 88 counterclockwise. This, in turn, rocks the yoke 92 clockwise and the stud 35 94 raises the rear end of pawl 95 until its end comes in front of a projection 104 on the arm 80 of pivoted yoke 78. Near the end of the forward stroke of the machine, the printing hammers 102 are rocked counterclockwise, when there 40 is an amount in the register, from the position of Fig. 2 and then released to drive the type bars to printing position. As the hammers move counterclockwise they engage the bail 99 and rock it counterclockwise which thrusts the pawl 95 to 45 the right as viewed in Fig. 2. The end of the pawl engages the projection 104 and rocks the yoke 78 counterclockwise whereupon the stud 76 on the arm 77 of yoke 78 rocks the pawl 74 clockwise from the position of Fig. 2. This movement 50 of the pawl 74 positions its nose 105 in the path of the end of the link 18 that moves rearwardly during the forward stroke of the machine. The parts are timed so that the pawl 74 moves to the position above explained prior to the time that 55 the link 18 reaches the end of its movement. The link then contacts the pawl and the pawl, being limited against pivotal movement on arm 73 by the engagement of a projection 106 on the pawl with an offset lug 107 on the arm 73, moves the 60 arm 73 with its yoke 70 and depresses the pin 61 to release the cash drawer automatically.

It will thus be seen that depression of the total or subtotal keys conditions certain parts which, in turn, are further conditioned by the printing mechanism so that operation of the machine automatically opens the cash drawer near the end of the forward stroke of the calculating machine.

As previously mentioned it is not desirable to open the cash drawer when the register is clear 65 and provision is made for automatically preventing such opening as follows:

The printing mechanism of the calculating machine described is provided with a special character printing portion which prints characters 70 75 to indicate the operation of the machine that

has just been performed. The special character printing portion of the mechanism includes a special type bar and a printing hammer similar to the rest of the printing mechanism but located on the right side of the other hammers, 5 viewing the machine from the front. When a total is taken, this special type bar is positioned to print a certain character and its hammer is operated in the usual manner. When the register is clear, if a total is taken, none of the hammers 10 that control type bars that print digits, are operated but the special character hammer is operated to print the special character indicating that the machine has been operated to take a total. 15

Referring to Fig. 2, it will be observed that the hammer for the special character type bar is cut away at 113 so that when it moves rearwardly, it will not engage the bail 99. Consequently, when only the special character printing mechanism is 20 operated, the bail 99 is not rocked and the pawl 95 is not thrust rearwardly. Accordingly, the pawl 74 on the releasing yoke 70 is not positioned in the path of the link 18 and the cash drawer will not be released. 25

"Single item" key

It frequently happens that a clerk sells only one item in which event it is not really necessary to take a total because the item is printed at 30 the time it is entered and, there being no other items, there is no occasion for a total. If the cash drawer could not be released except by taking a total as above described, it would be necessary for the clerk to go through the extra operation of depressing the total key and operating the machine before the cash drawer would open. This is an extra operation that is not desirable when only a single item has been sold. Accordingly, provision is made to automatically release 40 the cash drawer by the depression of a special "single item" key.

Positioned under the stem of the "single item" key 11 (Fig. 1) is a lateral lug on a lever 120 pivoted at its forward end on a side frame of the 45 machine. The rear end of this lever carries a stud 121 engaging in a slot in the end of the lever 122 pivoted on the shaft 31. The rear end of this lever has a downward projection 123 positioned in front of a stud 124 (Fig. 2) on the pawl 74. 50

When the "single item" key is depressed the lever 120 is rocked clockwise, which rocks the lever 122 counterclockwise. The downwardly projecting rear end 123 of lever 122 engages the stud 124 on pawl 74 and rocks the pawl clockwise 55 to position its nose 105 in the path of the link 18. Accordingly, when the machine is operated with the "single item" key depressed, the pawl 74 will be in the path of the link 18 and the cash drawer will be automatically released. 60

If desired, the "single item" key also functions as a "non-add" key in which event when the machine is operated after depression of the then "non-add" key, the cash drawer will be automatically opened and the item will not be entered 65 in the register but will be printed. For this purpose the lever 120, which is rocked clockwise by depression of the "single item" key, is provided with a downwardly extending portion (Fig. 1) positioned to engage a stud on the pawl 25 to disable said pawl when the "single item" key is depressed. Disablement of this pawl prevents the registers from being rocked into engagement with the actuator racks and thus "non-adds" the machine. When it is desired to have the machine 70 75

add at the time the "single item" key is depressed, the projection on the lever 120 is omitted, or the connections between this projection and the pawl 24 are eliminated, so that the pawl 24 is not disabled upon depression of the "single item" key.

Locking device

The control of the cash drawer heretofore described is a control that is usually made available for the clerks in a business establishment. It is desirable for the proprietor to have additional control of the cash drawer, and the present machine is equipped with a novel locking device by means of which the proprietor may lock the drawer completely so that it cannot be operated by any operation of the machine or, by the use of the same locking device, he can release the drawer automatically without operating the machine. This locking device is preferably key operated although it may be otherwise controlled if desired.

The locking device is mounted in the side of the housing 40 and comprises three pivoted tumblers 130, 131, and 132 (Fig. 3) having notches 133 in their outer ends adapted to engage over a lateral lug 134 on the link 69 that cooperates with the latch for the cash drawer in a manner that will be presently described. The tumblers 130, 131 and 132 are urged clockwise, as viewed in Fig. 3, by springs 135, the urge being in a counterclockwise direction in Figs. 4, 5 and 6. This urges the tumblers into engagement with the lateral lug 134 but they may be released by means of a flat key 136 having three projections 137^a, 138^a, and 139^a (Fig. 7) cooperating with complementary surfaces 137, 138, 139 (Fig. 4) on the tumblers. It will be understood, of course, that different combinations of projections and coacting surfaces can be used to get different locking combinations and that a different number of tumblers can be employed if desired. It will be noted, however, that the key is a flat key and that its projections can be turned to raise the tumblers to released position after which they pass the surfaces on the tumblers and allow the tumblers to drop back again. The tumblers have lower notched portions 140 (Figs. 4, 5, 6) for locking the lug 134 if the tumblers are raised too high by the use of a wrong key.

50 The key is also provided with a wide projection 141 (Fig. 7) for moving the link 69 forward and backward.

If the key 136 is inserted in the lock with the parts in normal or central position and turned clockwise from its Fig. 4 position to its Fig. 5 position, which would be counterclockwise in Fig. 1, the key first turns around to a position where it releases the tumblers 130, 131 and 132 from the lug 134 and, at about the same time that they are released, the wide projection 141 of the key engages a shoulder 142 on a dog 143 pivoted at 144 to the link 69 and urged counterclockwise as viewed in Fig. 4 by a spring 145. Further turning movement of the key moves the link 69 to the right as viewed in Fig. 4, or to the left as viewed in Fig. 1. The lateral lug 134 moves away from the notches 133 in the ends of the tumblers to the position shown in Fig. 5 where the tumblers drop back when released by the key and another set of notches 140 lock the link 69 in the position to which it has been moved. The link may be released by inserting the key and turning it in the opposite direction which raises the tumblers and allows link 69 to move back to its original position which it does under the influence of spring

66 (Fig. 3) which urges member 62 counterclockwise into engagement with the lug 68 on link 69.

If with the parts in normal or central position, the key is inserted and turned counterclockwise as viewed in Fig. 4, or clockwise as viewed in Fig. 1, the broad projection 141 of the key moves past the dog 143 without moving link 69. But, as viewed in Fig. 6, at the time the projections on the key release the tumblers, the broad projection 141 engages the cam shaped face 150 of a projection 151 on the link 69 so that further turning of the key forces the link 69 to the left, that is, to its Fig. 6 position, which would be a movement to the right or rear in Fig. 1. The tumblers are not allowed to drop back to a position to lock the link in its new position but are held upward by the lug 134 as shown in Fig. 6.

It will thus be noted, that, when the key is inserted in the lock and turned in one direction the link is moved in one direction and latched. 20 When the key is inserted and moved in an opposite direction the link is moved in the opposite direction but is not latched.

Referring to Fig. 3, it will be observed that the rear end of the link 69 straddles the stud 160 25 on the arm 57 of yoke 56. The link also has an upstanding and laterally projecting lug 68 engaging the projection 67 on the irregularly shaped member 62 pivoted at 64 to the plate 65 on yoke 56.

When the link 69 is in its normal or central position, which is the position where the locking device is in normal condition, the parts occupy the position of Fig. 3. If the key should be inserted in the locking device and rotated to the right as viewed in Fig. 3, the link 69 will be thrust to the right and its action in pushing on stud 160 will rock the yoke 56 counterclockwise which will result in rocking the latch 53 upward to release the cash drawer. Accordingly, by a simple clockwise turn of the locking device by means of the key 136, the cash drawer may be automatically released without the necessity for a machine operation. As soon as pressure on the key is released the parts return to normal under the urge of spring 55.

On the other hand, if the key is inserted and turned counterclockwise as viewed in Fig. 3, the link 69 will be moved to the left and locked in its left hand position. The rear end of the link 69 will move away from the stud 160 on arm 57 but arm 57 will tend to follow because it is urged clockwise by the spring 55. However it cannot move far because of the engagement of the top of a stud 161 on the member 65 with the cross frame member 42. As the link 69 moves to the left in Fig. 3, the lug 68 engages the projection 67 on the member 62 and rocks the member about its pivot 64 against the tension of spring 66. This moves the outer end of plate 62 clockwise out of the path of the releasing pin 69 with the result that the latch 53 for the cash drawer cannot be released no matter what the operation of the machine may be because depression of the pin 69 does not rock the yoke 56, there being no member directly under the pin. Accordingly, when the key 136 is inserted and moved counterclockwise, the cash drawer is locked and cannot be opened by a clerk no matter 70 how he operates the machine. It is necessary to have a key to unlock the locking device in order to get at the cash drawer or to restore the parts to a condition such that the cash drawer can be opened by a machine operation.

Modifications

If it should be desired to release the cash drawer for every operation of the machine regardless of the character of the operation, the above described machine can be quickly converted into one for accomplishing this result by substituting a yoke 170 shown in Fig. 8 for the yoke 70 of Fig. 3. This yoke is mounted on the same pivot stud and has an arm 171 positioned over the release pin 60. The other arm 172 of the yoke is not provided with a passby pawl but has a curved end 173 positioned so that it will be engaged by the end of the link 18 upon every rearward movement of said link. Accordingly, upon every operation of the machine the cash drawer will be released.

If it should be desired to release the cash drawer upon every operation of the machine except a "non-add" operation, the yoke 180 shown in Fig. 9 may be employed. This yoke is mounted on the stud 71 as a substitute for the yoke 70. It has an arm 181 positioned over the release pin 60. The other arm 182 of the yoke carries a pawl 183 having a stud 184 to which a spring is connected for urging the passby pawl to a position where the nose of the pawl will normally be in the path of the end of the link 18. In this form, the rear end 123 of the member 122, which is operated by depression of the "non-add" key, has a further offset portion 185 positioned under the stud 184. When the "non-add" key is depressed and the member 122 rocks counterclockwise, the pawl 183 will be rocked counterclockwise out of the path of the link 18. Accordingly, when the "non-add" key is depressed and the machine operated, the cash drawer will not be released but it will be released upon every operation other than an operation with the "non-add" key depressed.

It is to be understood that the construction shown is for purposes of illustration only and that variations may be made in it without departing from the spirit and scope of the invention as defined by the appended claims.

I claim:

1. In combination, a calculating machine having a register and means for taking a total therefrom, a cash drawer movable from closed to open position and vice versa, and means acting to automatically open said cash drawer when a total is taken on said machine, said means having provisions for preventing the opening of the cash drawer when a total is taken with the register clear.

2. In combination, a calculating machine having a register, a total taking means, a printing mechanism including a digit printing portion, said digit printing portion being controlled by said register and being operable to print a total only when there is an amount in said register, a cash drawer movable from closed to open position and vice versa, and means controlled by said total taking means and by said digit printing portion of said printing mechanism acting to automatically open said cash drawer when said digit printing mechanism is operated during the taking of a total.

3. In combination, a calculating machine having a printing mechanism including printing hammers, there being a special hammer for the character printing portion of said printing mechanism, a cash drawer movable from open to closed position and vice versa, a total key, and connections conditioned by depression of said

total key and set by movement of any of said printing hammers except the special character printing hammer for causing operation of the machine to automatically open the cash drawer.

4. In combination, a calculating machine having amount keys, a digit printing mechanism operating to print the amounts entered on said amount keys, a manipulative means for conditioning the calculating mechanism of said machine to perform a certain function, a cash drawer movable from closed to open position and vice versa, and means set by said manipulative means and conditioned by said digit printing mechanism for automatically opening said cash drawer when said calculating machine is operated to perform the function for which it is conditioned by said manipulative means.

5. In combination, a calculating machine having an operating means, a printing mechanism, and a total key, a cash drawer movable from closed to open position and vice versa, and means settable by said total key and conditioned by operation of said printing mechanism for causing operation of said operating means to automatically open said cash drawer.

6. In combination, a calculating machine having a printing mechanism including printing hammers, a cash drawer movable from closed to open position and vice versa, and means controlled by said printing hammers acting to automatically open the cash drawer when the printing hammers are operated.

7. In combination, a calculating machine having a printing mechanism including printing hammers, a total key, a cash drawer movable from closed to open position and vice versa, and means conditioned by depression of said total key and set by operation of said printing hammers for causing operation of the machine to automatically open the cash drawer.

8. In combination, a calculating machine, a cash drawer movable from closed to open position, means operated to automatically open said cash drawer upon operation of the machine when the machine is conditioned to perform a certain function, and a locking device for controlling said drawer opening means, said locking device acting, when in one position, to disable the control of said drawer-opening means by said machine and, when in another position, to automatically open said drawer independently of operations of said machine.

9. In combination, a calculating machine, a cash drawer movable from closed to open position, means operating to automatically open said cash drawer only when said machine is operated while conditioned to perform a certain function, and a key-controlled locking device for controlling said drawer opening means so that when the key is turned in one direction the calculating machine control of said drawer opening means is disabled and when the key is turned in the opposite direction the drawer is automatically opened without operation of the machine.

10. In combination, a calculating machine, a cash drawer urged to open position, a latch for restraining said drawer in closed position, means operated automatically by said machine to release said latch only when said machine is operated while conditioned to perform a certain function, and a locking device controlling the connections between said calculating machine and said latch so that, when the locking device is in one position, said connections are disabled and, when

- it is moved to another position, the latch is automatically released without an operation of the machine.
11. A cash machine provided with a calculating mechanism including a register, a total taking means for conditioning said calculating mechanism to take a total both when there is an amount in said register and when there is no amount therein, a cash drawer movable from closed to open position and vice versa, and means controlled by said register acting to automatically open said cash drawer only when said calculating mechanism is operated to take a total with an amount in said register.
12. In combination, a cash drawer housing having a top portion provided with a relatively large substantially rectangular opening in it, an upstanding flange around the edges of said opening, a calculating machine having a base pan fitting in said opening, an upstanding flange on the sides and ends of said base pan adapted to abut against the inside of the flange on said top portion of the housing, and a casing surrounding said calculating machine and fitting over the outside of the flange on said top portion.
13. In combination, a cash drawer housing having a top portion provided with a relatively large substantially rectangular opening, an upstanding flange around the edges of said opening, a calculating machine base pan positioned in said opening, said base pan having upstanding flanges on its sides and ends abutting against the inside of the upstanding flange of said housing, a sound deadening strip on the top edge of the flange on said base pan, and a casing surrounding said calculating machine having a shouldered flange resting on said sound deadening member and projecting below and outside of the flange on said housing.
14. A cash machine comprising a calculating mechanism including a register, a total taking means, a cash drawer movable from open to closed position and vice versa, means for automatically opening said cash drawer when a total is taken on said machine, and means controlled by said register preventing said drawer opening means from opening said drawer when a total is taken with said register clear.
15. A cash machine comprising a calculating mechanism including a register, a total taking means, a cash drawer movable from closed to open position and vice versa, a normally disabled means for automatically opening said cash drawer when a total is taken from said machine, and means controlled by said total taking means and by said register for enabling said drawer opening means when said total taking means is conditioned for total taking and when said register has an amount therein.
16. A cash machine comprising a calculating machine having an operating means, a register, a total taking means, a cash drawer movable from open to closed position, and means conditioned by said total taking means when it is set for total taking and by said register when there is an amount therein for operation by said op-

erating means to cause said drawer to be automatically opened only when said machine is operated to take a total with an amount in said register.

17. A cash machine provided with a calculating mechanism including a register, a total taking means, a cash drawer movable from open to closed position and vice versa, means controlled by said total taking means and by said register for automatically opening said cash drawer only when said machine is operated to take a total with an amount in said register, and a single-item key and connections operable to non-add said register and cause said cash drawer to be automatically opened as said calculating mechanism is operated when it has not been conditioned for total taking.

18. A cash machine having a calculating mechanism, a cash drawer urged toward open position, a latch for restraining said drawer, a member for releasing said latch, a second member associated with said first member and movable relative thereto, a third member operated by said calculating machine and operating on said second member to actuate said first member to release said latch, and a manually controlled device connected to said first two members, said device, when moved in one manner, acting to move said second member to disable it for operation by said third member and, when moved in another manner, acting to move said first member to release said latch.

19. A cash machine having a calculating mechanism, a cash drawer urged toward open position, a latch for restraining said drawer, a movable member for releasing said latch, a second member carried by and movable relative to the first, said second member being urged to a position in the path of a plunger operated by said calculating mechanism to move said members to release said latch, and a manually operable member connected to said first and second members and acting, when moved in one manner, to move said second member out of the path of said plunger and, when moved in another manner, to move said first member to release said latch.

20. In combination, a calculating machine having an operating means, a printing mechanism including printing hammers, a total key, a cash drawer movable from closed to open position and vice versa, and means settable by said total key and conditioned by operation of said printing hammers for causing operation of said operating means to automatically open said cash drawer.

21. In combination, a calculating machine, a cash drawer movable from closed to open position, means operated to automatically open said cash drawer upon operation of the machine when the machine is conditioned to perform a certain function, and a key operated lock for controlling said drawer opening means, said lock acting when in one position to positively lock the drawer in closed position and when in another position to automatically open said drawer independently of operations of said machine.
